(57) **CLAIM**

The ornamental design for a vehicle seat, as shown and described.

DESCRIPTION

FIG. 1 is an isometric view of a vehicle seat showing, in particular, the ornamental design thereof.

FIG. 2 is a front end view of the vehicle seat of FIG. 1.

FIG. 3 is a rear end view of the vehicle seat of FIG. 1.

FIG. 4 is a left side view of the vehicle seat of FIG. 1.

FIG. 5 is a right side view of the vehicle seat of FIG. 1.

FIG. 6 is a top plan view of the vehicle seat of FIG. 1; and,

FIG. 7 is a bottom plan view of the vehicle seat of FIG. 1.

The broken lines in the drawings depict portions of the vehicle seat that form no part of the claimed design.

1 Claim, 7 Drawing Sheets
